CLAIM

The ornamental design for a toilet seat lift, as shown and described.

DESCRIPTION

FIG. 1 is a front elevation view of a toilet seat lift showing my new design;

FIG. 2 is a rear elevation view;

FIG. 3 is a left side elevation view;

FIG. 4 is a right side elevation view;

FIG. 5 is a top plan view;

FIG. 6 is a bottom plan view; and,

FIG. 7 is a left side isometric view of a toilet seat lift showing my new design.

The broken lines of an exemplary toilet shown in FIG. 1 are for illustrative purposes only and form no part of the claimed design.
